Filed May 9, 1969, Ser. No. 17,101

Term of patent 14 years

Int. Cl. D22—02

U.S. Cl. D22—8

FIG. 1 is a side view of a ventilated sighting rib for guns showing my new design, the gun being shown in broken lines for illustrative purposes only.

FIG. 2 is a top view on an enlarged scale of the ventilated sighting rib for guns.

FIG. 3 is a side elevation thereof.

FIG. 4 is a sectional view taken along the line 4—4 of FIG. 3.

FIG. 5 is a sectional view on a further enlarged scale taken along the line 5—5 of FIG. 3.

FIG. 6 is a sectional view on the scale of FIG. 5 taken along the line 6—6 of FIG. 3.

FIG. 7 is a sectional view on the scale of FIGS. 5 and 6 taken on line 7—7 of FIG. 3.

FIG. 8 is a sectional view on a greatly enlarged scale along the line 8—8 in FIG. 2.

The notches on the outer portions of the rib, shown in FIGS. 2 and 8, are omitted in FIG. 3 and the rib is broken away in FIGS. 2, 3 and 4 for ease of illustration.

I claim:

The ornamental design for a ventilated sighting rib for guns, substantially as shown and described.
